United States Patent Office

Des. 177,724
Patented May 22, 1956

177,724

COMBINED CABINET AND EXTENSION TABLE

Abe J. Gaines, Glencoe, Ill., assignor to Saginaw Furniture Shops, Inc., Chicago, Ill., a corporation of Michigan

Application March 29, 1954, Serial No. 29,752

Term of patent 14 years

(Cl. D33—19)

Fig. 1.

Fig. 2.

Fig. 3.

Figure 1 is a front perspective view of a combined cabinet and extension table showing my new design with its removable hutch top in place.

Fig. 2 is a perspective view of a combined cabinet and extension table shown in Fig. 1 but with the hutch top removed and the cabinet element in open condition.

Fig. 3 is a perspective view of the combined cabinet and extension table with the hutch top removed and the table element in extended position.

I claim:

The ornamental design for a combined cabinet and extension table, substantially as shown and described.

References Cited in the file of this patent

UNITED STATES PATENTS

D. 151,963	Buckner	-----	Dec. 7, 1948
D. 154,920	Guild et al.	-----	Aug. 23, 1949
D. 167,884	Gaines	-----	Oct. 7, 1952

OTHER REFERENCES

Furniture Age, Oct., 1953, page 59, top right illustration.